HOOD CAPPING BOTTLES

Robert F. Huntley, Fulton, N. Y., assignor to
Oswego Falls Corporation, Fulton, N. Y., a corporation of New York

Application September 30, 1930, Serial No. 485,517

8 Claims. (Cl. 215—38)

This invention relates to the art of hood capping bottles, and by bottles I include containers composed in whole or in part of various materials and of various forms and structures, by the use of thin almost film-like sheet material, that is preferably transparent to render the indicia on the ordinary disk closures in the bottle mouths clearly visible; and the objects and nature of the invention will be understood by those skilled in the art in the light of the following explanations of what I now deem to be the preferred method of carrying out my invention, and in the light of the following explanation of what I now believe to be the preferred mechanical expression or embodiment of my invention from among other formations and structures within the spirit and scope thereof.

An object of the invention is to improve the bottle hood capped and bottle hood capping art, by attaining in said art advantages peculiar thereto through the production of a novel bottle hood capping method and film-like sheet hood cap having a margin capable of being contracted to hood-cap securing form and of being fixed in said secured form by strong unions directly uniting contacting surfaces of overlapping portions of said margin through coalescence of the material of such sheet surfaces where such cap is composed of thin sheet material characterized by its preferable transparency and thinness, resistance to moisture and dairy conditions, tensile strength, flexibility, toughness, resistance against severing or cracking by bending or creasing, and by its capacity, under suitable treatment, of becoming temporarily soft or tacky at its surfaces, and of directly uniting surface to surface by strong direct union through coalescence of the material thereof, when such softened surfaces are held pressed together until such merging surfaces are set hard.

And a further object of the invention is to improve the container hood capped and hood capping art, by the provision of a hood cap composed in whole or in part of thin sheet cellulose acetate composition, or its equivalent, secured in hood capped form on the bottle head by overlapping marginal portions of such cap united surface to surface by the coalescence of the material of such surfaces, with such marginal portions having inner surfaces in intimate adhering sealing contact with the container surface, where desired, and capable of being stripped therefrom, such adhering sealing contact being attained by holding such last named surfaces, while tem-

porarily in a softened condition, in intimate contact with the container surface until set hard.

The thin flexible sheet hood cap is composed, in whole or in part, of a suitable pre-existing sheet of cellulose ester composition, such as cellulose acetate, cellulose nitrate, or other thin sheet of equivalent composition or material that possesses the hereinbefore mentioned characteristics, or a preferably transparent base sheet of gelatin or its equivalent having thin permanent surface coatings possessing the aforementioned characteristics or composed of cellulose acetate or cellulose nitrate, although the cap composed of thin sheet homogeneous cellulose acetate composition is preferred.

With the foregoing and other objects in view, my invention consists in certain novel method steps, and in certain novel features, formations, and characteristics, as more fully and particularly hereinafter described and specified.

Referring to the accompanying drawing forming part hereof:

Fig. 1 is a plan view of a thin flat transparent hood cap disk composed of a sheet film of cellulose material, such as a cellulose ester of which cellulose nitrate and cellulose acetate are examples, or of a thin sheet of gelatin or equivalent material coated with permanently adhering films of preferably cellulose acetate.

Fig. 2 shows in side elevation, a hood cap disk, 30 the disk of Fig. 1, in partially skirted hood cap form.

Fig. 3 shows the neck and head portion of a bottle exteriorly covered or hood capped in accordance with my invention.

Fig. 4 is an enlarged cross-sectional view through a portion of the annular secured homogeneous cellulose acetate, or its equivalent, thin sheet margin or skirt of the hood cap, and the bottle portion backing the same, indicating the sealing adhering contact of set inner surfaces of the contracted secured hood cap sheet margin with the bottle surface, and also by dotted lines diagrammatically indicating set surface portions of overlapping folds of said sheet margin merged and strongly united by coalescence of the material thereof.

These film-like transparent sheets are tough, strong and yet sufficiently flexible for my purposes, and can be creased and folded for my purposes without severing or cracking or otherwise becoming pervious or perforate to the passage or absorption of moisture. These materials are, in fact, waterproof and moisture resistant and are not affected by atmospheric or other

temperatures to which bottled milk, and other filled and capped containers, for which my invention is adapted, are subjected, and furthermore such sheets or films are exceedingly clean and pleasing in appearance for container capping purposes, and are odorless and will not contaminate the contents of the container, and such sheets can be either obtained or manufactured of various thicknesses that may be required for various container capping requirements, although for ordinary bottle hood capping, film-like sheets of but a few thousandths of an inch in thickness will be employed.

Also, for the purpose of exteriorly covering or hood capping containers, the before-mentioned sheets or films possess the required strength and toughness, and resistance to moisture and atmospheric and bottling plant conditions to withstand treatment to which such capped containers are subjected during handling and shipment, and yet are not of such characteristics as to preclude ready removal or severing in the house or elsewhere, to permit access to and removal of the container contents.

The hood cap disks 1 and 2, are composed of pre-existing thin flexible imperforate sheets of cellulose acetate composition, or the equivalents thereof, possessing the characteristics substantially as hereinbefore set forth. The hood capping disk 1 is of large diameter, to provide a transparent center to cover and close the bottle or other container mouth and rest on and cover the lip surrounding said mouth, and an annular margin of the necessary radial width to permit folding and gathering thereof downwardly in the form of a depending annular skirt 3, around and covering the exterior rim or enlargement of the bottle head, and contraction of said skirt tightly under and around said rim, with the surplus material taken up along the dotted lines, Fig. 1, or otherwise by pleats, folds, or the like, 4, which can be pressed against the bottle surface backing the same, into tight overlapping formation, indicated by Figs. 3 and 4, to secure the hood cap margin or skirt, in contracted securing form on the bottle head.

Fig. 2 shows the thin cellulose ester sheet disk 2, in pre-formed partial hood cap or dished shape.

Any suitable means or method can be employed or followed, in applying the specified hood cap sheet to the bottle head and folding and gathering the margin thereof downwardly and to the exterior of the bottle head to final hood cap secured formation.

Usually, suitable annular mechanical gathering, folding, and clamping heads are employed for this purpose, to bring about the desired snug fit of the completed hood cap in final secured form on the bottle head.

Such clamping head will surround the contracted margin of the hood cap, and will hold the contacting temporarily softened or tacky surfaces of the overlapping marginal portions tightly pressed together and against the backing bottle surface, until such contacting portions have merged together by coalescence of the material thereof and set to permanent condition. The sheet surfaces to be thus merged, are, in this example, rendered soft or tacky, by slight application of a usually highly volatile solvent of the particular cellulose ester sheet material of which the hood cap is composed.

When a cap composed of one of the hereinbefore described, or an equivalent, film or sheet, is

applied to a container head, a small quantity of a volatile solvent for the particular material of the cap, is applied, preferably, only to the outer surface of the lower end portion of the cap skirt, and the cap molding or closing head contracts the creased, folded or gathered skirt under the bottle rim and compresses the same radially inwardly against the annular bottle surface, pressing together the solvent softened overlapped surfaces of the sheet into uniting welding contact and thus holding the same until the solvent has evaporated and the material has set and hardened with the previously softened surfaces merged together and permanently united by coalescence of the material thereof. The welding or uniting action takes place rapidly and the setting or hardening is quickly effected, as the solvents are highly volatile and the entire operation, where the solvents are concerned must be carried out with rapidity.

But a small quantity of solvent is applied, to avoid dissolving or perforating the film-like sheet, only sufficient to soften the same for welding or uniting purposes. The solvent is preferably applied, only to the outer surface of the lower portion of the cap skirt, to avoid possibility of causing the surface of the skirt to strongly adhere to the bottle or container surfaces with which it comes in contact, and objectionably fouling the container surfaces on removal of the cap, however my invention does not preclude applying the solvent to both the inner and outer surfaces of the cap particularly where, to meet certain conditions, it is desired to seal the cap skirt to the container surface surrounded and engaged thereby.

It is only necessary to apply the solvent to those portions of the outer surface of the cap skirt, that do not contact with the container surfaces, where the folds of that skirt are pressed radially inwardly or together by the capping head, at which points the solvent softened material will almost instantly weld or flow into each other when said surfaces are pressed together by the contracting sealing tool or head. However, as a matter of convenience, I have applied the volatile solvent completely around the desired portion of the exterior surface of the cap skirt to soften the same.

I have found that when some of the material from which the cap is made is dissolved in the solvent before the solvent is applied to the cap a better seal is effected.

If during the application of this cap an excess of solvent is applied, it may be seen that the solvent might dissolve a hole in the film. To overcome this and retard the drastic action of the solvent on the film, a material known to the trade as a non-solvent is used. This is a substance which as the name signifies will not dissolve the film but which is readily miscible with the solvent. By using these non-solvents it is possible to get a solution with the minimum amount of solvent in it. Inasmuch as the solvent is the expensive item these non-solvents decrease the cost.

Some of the non-solvents which may be used are: benzol, toluol, xylol, and solvent naphtha.

When a piece of any of the above films is moistened with a solvent for that film it will immediately soften and if enough solvent is added, it will dissolve completely. If there is just enough solvent applied to the surface of one of these films to soften it, the film may be joined to another film by the application of pressure.

For welding a disk or sheet composed of or having a surface coating of cellulose nitrate, I usu-

- ally employ as a solvent, acetone, ethyl acetate, butyl acetate, anyl acetate, butyl propionate, among others; and for a sheet of cellulose acetate, one of the following solvents, among others, 5 namely;—acetone, triacetin, ethyl lactate, methyl acetone, methyl acetate.
- If the hood cap secured on the container head, as before described, is composed of a very thin light weight sheet of the cellulose material, the 10 secured cap can be easily removed from the container head by twisting and tilting and lifting off the cap by hand. Where the secured cap is composed of a thicker heavier cellulose material sheet, of greater tensile strength than the 15 first named sheet, it may be sometimes necessary to puncture the top portion of the cap by the use of a sharp instrument and then tear down the cap skirt to permit expansion of the cap skirt and removal of the cap from the container head.
- 20 The cellulose material is tough and while resistant against puncture is more easily torn.

What I claim is:—

1. A bottle having a head, and a hood cap disk closing and covering said head and having a depending annular skirt fitting and contracted under said head and held in hood cap securing form and condition by the directly contacting faces of overlapping portions of said skirt merged together by coalescence of the material thereof, 25
2. said hood cap disk formed by a thin strong transparent sheet of cellulose acetate material that is dry, non-absorbent and flexible.
3. A flexible transparent cap for milk bottles consisting of a sheet of a homogeneous cellulose ester having its central portion extending across 35 the top of a bottle and having its margins conforming to the contour of the neck of the bottle and united by coalescence of the material.
4. A protective hood for milk bottles having 40 the usual printed cap forming the official label comprising a sheet of homogeneous transparent material having a smooth portion over the printed cap and having the margins surrounding the smooth portion formed in overlapping folds 45 having the adjacent surfaces united by coalescence of the material.
5. The combination with a bottle of the character described, of a hood cap consisting of transparent cellulose ester sheet material having a pleated skirt portion free from deposit forming adhesive and sealed to the bottle neck solely by a partially dissolved and dried surface portion 50

of the skirt, the cap having the property of readily stripping from the bottle without leaving a deposit on the bottle neck.

5. In the method of hood capping containers, those steps which comprise applying to the container head a hood cap blank of transparent flexible thin sheet material having at least a face of cellulose ester material; gathering and contracting the skirt of said blank to and under the container head in overlapping folded layers, softening the adjacent surfaces of overlapping layers of the skirt sufficiently to render them tacky, and holding said overlapping layers together until said faces are integrally united by coalescence of the material. 15

6. In the method of hood capping containers, those steps which comprise applying to the container head a hood cap blank of transparent flexible thin cellulose ester material, gathering and contracting the skirt of said blank to and under the container head in overlapping folded layers, softening the adjacent surfaces of overlapping layers of the skirt sufficiently to render them tacky by applying thereto a solvent for the material, and holding said overlapping layers 20 together until said layers are integrally united by coalescence of the material. 25

7. In the method of hood capping containers, those steps which comprise applying to the container head a hood cap sheet of transparent flexible thin cellulose acetate material, gathering and contracting the skirt of said sheet to and under the container head in overlapping layers, softening the adjacent surfaces of overlapping layers sufficiently to render them tacky, and holding 30 said overlapping layers with said softened surfaces contacting under pressure until said surfaces merge together by coalescence of the material thereof and set to hardened condition. 35

8. A bottle hood cap composed of a transparent 40 thin cellulose acetate sheet having its central portion covering the bottle mouth and its depending margin surrounding and conforming to the contour of the exterior bottle head surface and having direct adhering sealing surface contact with said bottle head surface, the annular marginal portion of said sheet being secured in contracted form around said bottle surface by overlapping portions the contacting surfaces of which are united by coalescence of the material thereof into hardened unions. 45
